UNITED STATES PATENT OFFICE

1,999,022

FIRE GUARD FOR MOTION PICTURE MACHINES

George B. Reay, Chicago, Ill.

Application October 30, 1933, Serial No. 695,805
Renewed February 18, 1935

6 Claims. (Cl. 88—17)

This invention relates to improvements in fire guards for motion picture machines. One object of the invention is to provide a fire guard having a spring actuated blade for severing the film and closing the film slot, to confine the fire within the projection chamber of the machine, the blade being held normally in retracted position by a segmental pinion having an un-toothed portion which serves as a stop to limit the movement of the blade in both directions of travel, that is, when retracted manually to set position and especially when actuated to sprung position by the spring. As the blade is relatively thin and the pinion, which is located within a longitudinal slot in the blade, is of like thickness, it is desirable that the correspondingly thin points of the teeth will not be subjected to the stresses imposed by the blade at its limits of travel since the deforming of the teeth might cause the teeth of the pinion to bind with the rack formed in one side of the slot and delay, if not prevent, the operation of the blade in case of fire.

Another object of the invention is to provide a spindle mechanism of improved construction which provides a double bearing for the pinion and which facilitates the assembly of the spindle mechanism.

A further object of the invention is to provide a fire wall adjacent the film opening in the upper guard which in cooperation with a pair of film guide rolls prevents fire from a burning film within the projection chamber from flashing horizontally to ignite a portion of the film adjacent the film opening and thus traveling through the film opening to the upper magazine before the blade has been sprung to closed position.

A further object of the invention relates to the provision of said pair of film guide rolls adjacent the lower edge of the device and as far removed from the film opening as feasible to obstruct the progress of the rising flames of the burning film toward the portion of the film adjacent the film opening and thus providing an additional instant of time in which the blade may act to prevent ignition of the film in the upper magazine.

Other objects relate to various features of construction and arrangement of parts which will be apparent from a consideration of the following specification and accompanying drawings wherein:

Figure 1 is a fragmentary view of a motion picture projecting machine showing my improvements positioned therein.

Figure 2 is a top plan view of the upper fire guard with a portion of the cover plate broken away.

Figure 3 is a vertical sectional view taken on line 3—3 of Figure 2. 5

Figure 4 is a bottom plan view of the upper fire guard.

Figure 5 is a broken longitudinal section showing the film cutting blade in sprung position.

Figure 6 is a transverse sectional view taken on line 6—6 of Figure 3. 10

Figure 7 is a top plan view of the lower fire guard.

In the drawings 10 indicates generally the projecting chamber of a conventional motion picture machine which is provided with an upper film reel 11 and a lower film reel not shown. The upper reel is customarily secured to the upper end of the casing of the projecting chamber 10 by means of a well 12, but in employing 20 my upper fire guard which is indicated generally by the numeral 13, the fire guard is located between the well 12 and the upper end of the casing 10. 15

The well 12 is provided with a conventional slot 12a through which the film is passed in threading the machine, and a similar slot 13a is provided in the guard 13 in registration with the slot 12a. The construction of the projecting apparatus forms no part of the present improvements and hence is shown only fragmentarily in the drawings. 25

The film, however, passes around a sprocket 14 in the chamber and is provided with a loop 15 in the conventional manner to avoid imposing 30 stresses on the film as the same passes through the Geneva movement.

The film passes through the lower fire guard indicated generally by the numeral 16 which is placed within the casing 12 and is provided with a film slot 16a through which the film extends to the lower take up magazine or first to the sound mechanism, if such be employed. 40

The fire guard 13 comprises a housing or casting having a top 17 and provided with a downwardly extending perimetrical flange 18. 45

The upper surface of the top 17 is provided with a channel or guideway 19 in which is positioned a sliding blade 20. A spring 21 is arranged to force the blade forwardly or to the right as viewed in Figures 2 and 3 across the film slot 13a, for the purpose of closing the slot and severing the film to prevent progress of fire from the projecting chamber to the film reel 11. 50

A cover plate 22 which is attached to the hous- 55

ing 13 by screws 22a overlies the blade and spring as shown in Figure 3.

The blade 20 as shown clearly in Figure 2, is provided with a slot 23 along one edge of which 5 is formed a rack or teeth 24. The ends of the slot preferably are curved as shown at 25 and 26 for the purpose hereinafter stated.

10 Positioned in the slot 23 is a segmental pinion 27, the teeth of which mesh with the rack 24. The pinion is mounted on a short shaft 28, the upper end of which projects into and is journaled in an opening in the cover plate 21. The lower end of the shaft is provided with 15 a slotted head 29 which is journaled in a stationary tube 33 welded or swaged or otherwise secured in an opening in the top wall 17 of the housing 13.

15 As shown, the diameter of the tube 30 is less than the diameter of the pinion 27 and hence the 20 latter and the headed shaft will be confined between the wall 17 and the cover plate 21 and in the plane of the blade, with the teeth of the pinion always in engagement with the rack 24.

20 A spindle or shaft 31 having a head 32 adapted to be set in the slot of the head 29 is journaled in the tubular sleeve 33 also located in the tube 30, and held therein by a set screw 39a.

25 A fuse arm 34 is secured to the upper end of the sleeve 33 by riveting over a central reduced 30 extension 33a of the sleeve. The arm 34 has a portion 34a bent over to engage a notch in the lower edge of the tube 30 to prevent rotation of the arm. Secured on the outer end of the rotatable spindle 31 is a second fuse arm 35 which 35 when turned operates the spindle 31 and likewise the shaft 28 and the pinion 27.

30 By providing the detachable connection between the spindle 31 and the shaft 28 as above described, the assembly of the apparatus is simplified. The gear 27 is of larger diameter than 40 the tube 32 and hence is positioned from the top as viewed in Figure 3. With the teeth of the pinion in mesh with the rack 24 of the blade, the cover plate 21 is secured in position.

45 The fuse-holding blade-retracting unit comprising the spindle 31, sleeve 33, and the two arms 34 and 35 can be assembled as a unit and inserted in the lower end of the tube 30, and secured in position by means of the set screw 30a.

50 In Figure 4 the ends of the stationary arm 34 and the movable arm 35 are shown reduced at their extremities for engaging the ends of a fuse 36. This fuse may be of fusible metal or two portions of metal held together by a second fusible 55 material as illustrated in the drawings, or it may be of inflammable material such as celluloid, for example.

55 When the arms are in the position shown in Figure 4, the pinion 27 is in the position shown in Figure 2; that is, it engages the right hand teeth of the rack and holds the blade 30 clear of the film opening 13a.

60 Should fire occur in the projecting chamber 10 and liberate the movable arm 35, the spring 21 will move the blade to the right as viewed in Figure 2, to the position shown in Figure 5, and thus close the film opening 13a and sever the film to prevent the passage of the fire through the film opening and into the upper magazine 11.

65 70 When the blade 20 moves to the right as viewed in Figure 2, under the action of the spring 21, the pinion 27 will be rotated counter-clockwise as the rack moves to the right whereby the curved un-toothed portion of the pinion will engage the 75 wall 25 of the slot to limit the movement of the

blade. The teeth of the pinion therefore are not subjected to action which will tend to mar or deform the same, which would interfere with the free operation of the blade and possibly cause failure of the apparatus to function as intended. 5

In re-setting the device the movable arm 35 is swung counter-clockwise as viewed in Figure 4 from the dotted line position to the full line position, and a new fuse placed over the ends of the arms. The movement of the arm 35 as mentioned retracts the blade against the action of the spring to the position shown in Figure 2. In this position it will be noted that the un-toothed portion of the pinion 27 will abut the curved wall 26 of the slot 23 and thus limit the movement of the 15 blade to the left.

By the arrangement described, the pinion acts as a stop for the blade in its movements in both directions and thus other stop means for the blade is not required. As noted, the blade 20 may be 20 relatively short and when in set position will lie entirely on the left hand side of the slot 13a, as viewed in Figure 2.

To facilitate access to the arms 33 and 35 for 25 re-fusing one flange of the housing 13 is provided with a door 37 which is hinged at 38 to the wall and is provided with a spring pressed catch 39.

Thus as shown in Figure 1 with the conventional door 10a of the projecting chamber 10 30 moved to open position, and the door 37 also open, considerable room for the hand is provided for retracting the movable arm 35 and re-fusing the device.

To facilitate the fusing or ignition of the fuse 35 when a film catches fire, a flame deflecting wall or web 40 is provided preferably integral with the top wall 17 of the housing. Thus when the flames reach the loop 15 of the film, and rise into the left hand portion of the member 13, as 40 viewed in Figure 3 and tend to spread out along the wall 17, the depending fire wall 40 will tend to direct the flames downwardly toward the fuse to facilitate the fusing or ignition of the same. This wall quickens the action of the mechanism 45 and causes the blade to move across the opening 13a to close the same and sever the film before the progress of the flames has passed upwardly through said opening.

An additional fire wall 41 is provided which 50 extends transversely between the longitudinal flange 17. This wall is provided to prevent the flame from flashing across from the burning loop 15 and igniting the film adjacent the film opening 13a, and thus permitting the flame to escape 55 beyond the fire guard before the blade has been released. To further obstruct the progress of the flames of a burning film from passing through the slot 13a a pair of rollers 42 are provided between which the film passes. These rollers are 60 mounted on shafts 43 which are secured in the bosses 44 cast integrally with the flanges 17. Thus as viewed in Figure 3, the left hand roller 42 will be seen as being located rather close to the lower edge of the wall 41, and thus will deter 65 the passage of the flame around the lower edge of the wall.

The flame in rising along the film toward the film opening will be retarded slightly by the two rollers 42, and will thus provide another instant 70 of time for the fuse 36 to give way and the blade to function.

The lower fire guard 16 is provided with an upstanding tube 45 which is secured to the cover plate 46. A blade similar to blade 20 is also 75

provided and is operated by a similar pinion and spindle and shaft mechanism. A stationary arm 47 similar to the arm 34 and a swinging arm 48 similar to the arm 35 are also provided and need not be further described.

5 The lower guard also preferably is provided with a guide roller 49 mounted on a shaft 50 which is secured at its ends in studs 51.

10 Beneath the film slot 16a two additional guide rollers 52 are provided to prevent the film from striking the edge of the slot and becoming scratched.

15 As shown in Figure 7, one edge of the lower guard is provided with recesses 53. These are merely to accommodate the device to different types of projecting machines.

20 While I have shown and described my improvements for the purpose of illustration, I do not wish to be restricted specifically thereto except as so limited by the appended claims.

I claim:

25 1. A fire guard comprising a housing having a film opening therethrough, a spring actuated blade in said housing adapted to move across said opening to close the same and sever the film, said blade having a longitudinal slot therein provided with a rack on one side thereof, a segmental pinion in said slot having teeth engaging said rack, the untoothed portion of said pinion being arranged to engage the end walls of said slot to limit the movement of said blade in both directions of movement thereof and a spindle operatively connected with said pinion and provided with a manually operable fuse engaging arm for effecting the retraction of said blade.

30 2. A fire guard comprising a housing having a film opening therethrough, a spring actuated blade in said housing adapted to move across said opening to close the same and sever the film, said blade having a longitudinal slot therein provided with a rack on one side thereof, a segmental pinion in said slot having teeth engaging said rack, the untoothed periphery of said pinion being arranged to engage an end wall of said slot to limit the movement of said blade under the action of said spring, and a manually operable spindle having a fuse arm for rotating said pinion to retract said blade.

35 3. A fire guard comprising a housing having a longitudinal channel in the upper side thereof and having a film opening therethrough, a spring actuated blade in said channel movable over said opening to close the same and sever the film, a cover over said blade, said blade having a longitudinal slot therein provided with a rack in one

5 wall thereof, a pinion in said slot having a shaft journaled at its upper end in said cover and at its lower end in said housing, a spindle detachably connected with said shaft for turning said pinion to retract said blade, and a manually operable arm on said spindle adapted to engage one end of a fuse for holding said blade in retracted position.

10 4. A fire guard comprising a housing having a film opening therethrough, a slideable spring actuated blade in said housing adapted to move across said opening to close the same and sever the film, manually actuatable means operably connected with said blade for retracting the same against the action of the spring, said means comprising an arm for engaging a fuse for retaining said blade in retracted position, and a flame deflecting wall for directing flame from a burning film toward said fuse.

15 5. A fire guard comprising a housing provided with a film passage therethrough, a spring actuated blade movable across said opening to close the same and sever the film, said housing having a top wall and depending side walls, fuse restrained mechanism depending from said top wall 25 and operatively connected with said blade for holding the same in retracted position, a fire wall extending transversely of said housing between opposite side walls thereof and located between said film opening and said fuse mechanism for preventing the passage of the flame of a burning film along said top wall to the film adjacent the film opening, and a flame deflecting wall adjacent said fuse mechanism for directing flame toward the fuse.

20 6. A fire guard comprising a housing having a top wall provided with a film opening therethrough intermediate the ends thereof, a spring actuated blade movable across said opening to close the same and sever the film, a fuse restrained mechanism depending from said housing at one side of said opening and being operatively connected with said blade for holding the same in retracted position, a depending fire wall located between said mechanism and said opening 40 to prevent the passage of the flame from burning film laterally along said top wall to the film adjacent the film opening, a pair of rollers between which the film passes located adjacent the lower edge of said housing to retard the vertical passage of flame toward said film opening, and a flame deflecting wall adjacent said mechanism for directing flame toward the fuse carried by said mechanism to effect the release of said blade.

35 GEORGE B. REAY. 55
